Application January 8, 1940, Serial No. 312,811
 In Germany January 17, 1929

14 Claims. (Cl. 179—27)

The present invention relates to automatic telephone systems in which the connections incoming from outside exchanges are set up over numerical impulsing devices used in outgoing connections from this exchange station. Thus for setting up an outgoing connection, after selection of the required subscriber's line over a setting path and connection of a numerical impulsing device, also used for outgoing connections, to the selected line, this numerical impulsing device is set by the dialled impulses, which are controlled by that station setting up the incoming connection, e. g. by an operator, and are sent over the setting path. The numerical impulsing device then has access to the calling line over means used only for incoming connection directions.

With this system therefore, for setting up the connecting path it is necessary to have the impulse series characterising the calling exchange as well as the impulses corresponding to the number of the required subscriber. If this exchange receives calls from several outside exchanges to pass to line then, especially in heavy traffic, mistakes in characterising the calling exchange are easily possible, for the calling subscriber sends only the number of the required subscriber.

If the impulses for setting up the incoming connection are sent out, for example from an impulse transmitter by a key set, it is necessary to provide additional switch means in order that the necessary impulse trains should be sent out for gaining access to the required subscriber's line. Switch means must be provided which make possible the transmission of the additional numerical impulse train or trains, the number of which are adjusted to correspond with the selecting stage over which the line is reached. As a rule the line is connected to the first group selector or in smaller systems to a certain bank of the final selector. In order not to decrease the capacity of the system too greatly it may also be necessary to connect the lines to the second or third group selectors, or, if a smaller system is in question to individual line contacts of the final selector. Therefore two or three additional numerical impulse series are necessary.

The additional impulse for setting the impulsing device, also used for outgoing traffic, cannot be sent out directly after dialling if the required subscriber's line is engaged. The numerical transmitter must therefore be furnished with further switch means which give rise to the transmission of the additional impulses only if after notification of the required subscriber, who however is engaged in the existing connection is dis-

connected and a free impulse receiver is ready to receive the dialled impulses for setting up the talking connection.

The present invention removes all these difficulties in that after selecting the line of a subscriber required for an incoming connection over a setting path and connecting a numerical impulsing device also used for outgoing connections to this line, under the control of a marking signal for the incoming direction, the switch means functioning to set up the connection are operated and automatically set the numerical impulsing device on the calling line.

In using the arrangement according to the invention the station setting up of the incoming connection need only effect the transmission of impulses corresponding to the required subscriber. The impulse senders are provided with no switch means for other purposes (additional impulses and transmission of the same dependent on special conditions). False connections are moreover prevented effectively while the marking of the operator is made easier.

According to the invention the capacity of the system in which the incoming connecting traffic passes over the numerical impulsing device used for the outgoing connecting direction can be appreciably increased in that the lines are not provided with particular accesses for the outgoing and incoming directions which are attainable over contact groups designated by different digits. The same access means to the junction line is seized over the numerical impulsing device for outgoing and also incoming connections.

In the drawings two embodiments of the invention are shown. Figs. 1 and 2 show telephone substation equipment in which the lines to outside exchanges are connected to the first group selector and are provided with separate accesses for outgoing and incoming directions.

In Fig. 3 a telephone substation equipment is shown in which the connecting lines to outside exchanges have only one access means which can be reached over the first group selector and is used for incoming as well as outgoing connecting directions.

I. THE EMBODIMENT ACCORDING TO FIGS.
 1 AND 2

1. OUTGOING CONNECTION

When the subscriber T_{n1} makes a call the relay R_1 is energised and in known manner gives rise to the setting of the preselector IVW . In the test circuit: +, wiper 1, contact segment 2, con-

tacts 3rl, windings I and II of the relay T1, wiper 4, conductor 5, contacts 6a1, 7kgw, —, the relay T1 is energised, disconnects the group selector IGW by short-circuiting its high resistance winding I at contact 8t1, stops the preselector and switches through the speaking conductors at contacts 9t1, and 10t1, by disconnecting the calling bridge.

In the microphone feeding circuit the relay A1 is energised but not the differential relay X1. At contact 6a1 a short circuit of relay C1 is removed. The impulsing contact 11a1 is opened and at contact 12a1 the slow to release relay V1 is switched in. Relay V1 is energised, closes its contact 13v1 in the circuit of the control relay V2 which however is short-circuited as long as contact 12a1 is closed. At contact 15c1 after the off-normal contact 7kgw is opened a holding circuit operating for the relays C1 and T1, is completed. At contact 17c1 the circuit for the vertical magnet and at contact 18c1 the test circuit are prepared.

The accesses for the connecting line in the outgoing direction are connected in the decade X of the group selector. The subscriber Tn1 transmits a suitable number of impulse series. Relay A1 transmits these impulses to the vertical magnet H1: +, contacts 11a1, 17c1, vertical magnet H1, rotary off-normal contact 18w, —. At the first numerical impulses when contact 12a1 opens and contact 19a1 closes relay V2 is energised: +, contact 13v1, relay V2, winding I, contact 19a1, resistance 20, —. It remains energised during the impulse series and prevents the premature operation of the rotary magnet D1 by opening the contact 21v2. At the end of the numerical impulse transmission and restoration of relay V2 the rotary magnet D1 is switched in: +, interrupter, contacts 22p1, 21v2, rotary magnet D1, off normal contact 23kgw, —. When the wiper of the group selector reaches the contact of a further junction line VL, the test relay P1 is energised: +, relay V1, winding II, contact 18c1, windings I and II of the relay P1, wiper 24, contact 25, locking conductor 26, contact 27hr, winding I of the relay C4 and parallel to this: contact 28v7, differential winding II of relay C4, contacts 29v7, 30hr, 146v8, —. The test relay P1 stops the group selector by opening the contact 22p1. It locks the connecting line by short-circuiting its high resistance winding I at contact 31p1, disconnects the relays A1 and X1 at the contacts 32p1, and 33p1 and switches through the speaking conductors at contacts 34p1 and 35p1. The contact 36p1 in series with the contact 14v1 in the holding circuit of relays C1 and T1 is closed. Relay A1 restores and short-circuits the relay C1 at contact 6a1 so that it restores. The relay T1 however remains energised over: 6a1, 14v1, 36p1, 16.

At the junction line VL the seizing relay C4 switches through the speech conductors, at the contacts 37c4 and 38c4. The calling subscriber is fed with current over the relay A4 which switches in the relay V7, at contact 39a4. This opens the contacts 28v7 and 29v7. Moreover, a holding circuit is completed over both windings I and II and the contact 40c4 for the relay C4 and also for the relay P1 of the group selector. The contact 41a4 in the upper conductor of the junction line VL is closed. At contact 42v7 the choke Dr1 in the bridge between the two conductors of the connecting line is connected and thereby the call signal is transmitted to the distant exchange station. Other contacts controlled by

the relays C4 and V7 are ineffective in outgoing connections.

2. INCOMING CONNECTION

(a) Subscriber's line free

- When a call is made over the junction line VL the relay Ar is energised and switches in a holding relay Hr at contact 45ar the relay holding itself energised in a holding circuit at contact 45hr: +, contacts 160v8, 48v1, 47tr, 46hr, relay Hr, —. At contact 49hr the engaged lamp BL1 and at the contact 50hr, the calling lamp AL are switched in. The junction line VL is locked against seizing over a group selector by the opening of contact 30hr. At contact 27hr the locking conductor 26 is disconnected and at contact 51hr the locking conductor 52 is connected in the incoming direction and causes the operation of the locking relay C4 for the junction line VL. The calling of the required subscriber after this connection to the calling junction line VL causes relay Ra to be switched in: —, contact 53tr, winding I of relay Ra, contacts 54ra, 55hr, 56c4, +. Relay Ra holds itself energised at contact 57ra opens the contacts 58ra, 59ra, in the speaking conductors, connects its winding II at contact 60ra to the upper speaking conductor and at contact 61ra connects the resistance 62 connected to positive to the lower speaking conductor. The operator operates the supervisory switch AT. Relay Ab is energised and holds up over: +, contacts 63tr, 64c4, 65ab, relay Ab, —. The contacts 66ab, 67ab, are opened and the contacts 68ab and 69ab are closed. The speaking apparatus BA of the operator is connected across the junction line VL. At contact 70ab the choke Dr2 is connected across the two speaking conductors. At contact 71ab the call lamp AL is disconnected. Further the circuit for the engaged lamp is opened at the contact 74ab. By closing the contact 75ab the setting up of the connecting path to the group selector is completed preparatory to calling over the junction line VL.
- When the operator has obtained the necessary information, she presses that key of the set of keys at the exchange which corresponds to the number of the required subscriber. In metering transmission the contacts e are switched over into the operated position, and are controlled either by a relay or mechanically from the metering transmitter. At contact 76e relay F1 is switched in and by closing the contacts 79f1, 80f1 and opening the contacts 77f1, 78f1 the conductors 83, 84 leading to the first selector PGW of the setting path are switched over to the metering transmitter and the relay F2 is switched in at contact 85f1, so that the contacts 81f2, 82f2 and 87f2 are closed. At contact 88e the relay G is switched in over its winding I. It closes the contact 89g in circuit of its winding II, contact 90g in the circuit of relay F2, contact 91g in the circuit of relay F1 and the contact 92g in the circuit of relay G1. Over the contacts 89g and 92g no switching operations are carried out for the moment since the contacts 93e and 94e are open. The following circuit is set up over the contact 95e: —, impulsing contact i, contacts 95e, 96g1, 80f1, 82f2, conductor 84, contact 97p2, relay A2, +. The relay A2 switches in the relay V3 at contact 98a2 and removes the short-circuit for the winding of relay C2 at contact 99a2, the relay responding: —, resistance 86, contact 87f2, conductor 100, relay C2, resistance 101, +. The relay C2 prepares

for the setting of the group selector PGW of the setting path and prepares a test circuit at the contact 102c2. The setting magnets of the selector PGW are not shown. Numerical impulses are produced by opening the contact *i* and cause relay A2 to restore so that the impulses are transmitted further to the driving magnet. In known manner a control relay is also energised which, during the impulse series, prevents the operation of the test relay P2 by opening the contact 103v4. At the end of the impulse series contact 103v4 is closed and the following locking circuit is completed: —, contacts 102c2, 103v4, relay P2, wiper 104, winding I of relay C3, and parallel to this, contacts 105v5, 106a3, winding II of relay C3, off-normal contact 107kplw, +. The relay P2 opens the contact 97p2 and switches through the setting path at the contacts 108p2 and 109p2. Contact 110p2 is opened and so prevents a short-circuit of the locking relay C2 at contact 99a2 when relay A2 restores. In the station line selector PLW relay A3 responds over its lower winding, the conductor 84 and the contact *i* in the metering transmitter. It opens the contact 106a3 and switches in the relay V5 at contact 111a3 and also opens contact 105v5. The relay C3 prepares the holding circuit at contact 112c3 over both its windings I and II after the off-normal contact 107kplw is opened and prepares the test circuit over the winding I of relay P3 and a circuit connecting up relay Y by closing the double armature operating contact 113c3.

During the first numerical impulse series which sets the line selector a slow relay, not shown, is energised which opens the contacts 114v6 and 115v6. At the end of this impulse series the switching over of the line selector to the second setting magnet is carried out in known manner, when the relay, not shown, restores. The second impulse series, during which contacts 114v6 and 115v6 are again opened, causes the setting of the line selector PLW on the connecting line of the required subscriber T_n . At the end of this impulse series the contacts 114v6 and 115v6 are closed. The connecting-up relay Y is slow to energise. It is therefore not energised when the test relay P3 is energised owing to the selected connecting line being free: —, contacts, 113c3, 114v6, winding I of relay P3, wiper 116, contact 117, rest contact 118 of the preselector IVW, wiper 4, windings II and I of relay T1, wiper 1, +. On account of the high resistance of winding I of relay P3 relay T1 is not energised in this circuit. In the line selector PLW the circuit of the connecting-up relay Y is broken at contact 119p3. At contact 121p3 a holding circuit is prepared over the winding II of relay P3. At contacts 122p3 and 123p3 the disconnection of both windings of bridge relay A3 follows and at the contacts 124p3 and 125p3 both conductors of the setting path are switched through. Relay A3 restores and disconnects relay V5. At the contacts 106a3 and 105v5 both windings I and II of relay C3 are short-circuited. The relay C3 restores. The relay P3, whose winding I is disconnected at contact 113c3 remains energised: +, winding II of relay P3, contacts 121p3, 106a3, 105v5, wiper 104 of PGW, relay P2, contacts 103v4, 102c2, —.

In the metering transmitter the contacts *e* return to the rest positions when all the numerical impulses are transmitted. Before contacts 88e and 95e are opened the contact 93e is closed. The relay G is held energised owing to the selected junction line being free and the line se-

70 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

lector PLW being switched through to the contacts 124p3, and 125p3: —, contact 126t1, conductor 127, wiper 128, contacts 129y, 124p3, wiper 130, contact 108p2, conductor 83, contacts 81f2, 79f1, winding II of relay G, contacts 89g, 93e, 96g1, 80f1, 82f2, conductor 84, contact 109p2, wiper 131, contact 125p3, 132y, wiper 133, conductor 134, contact 135t1, relay R1, +. The relay R1 is energised and causes the seizing of a free group selector IGW in an outgoing direction. At the exchange the operator maintains contact 92g closed so that the relay G1 with its slow armature attraction is energised: +, relay G1, contacts 92g, 94e, resistance 136, —. Relay G1 opens at contact 137g1 the shunt for its winding I switches through over its contact 138g1 its winding II to the contact 80f1 and thereby to the conductor 84 and holds relays F1 and F2 energised over the contacts 139g1 and 140g1.

20 In the group selector IGW, since after the response of relay C1 at the exchange the operator disconnects the bridge between the conductors 83 and 84, only negative is connected to the conductor 84 and besides the relay A1 relay X2 is energised over its winding II. At contact 12a1 relay V1 is connected and completes a holding circuit over the winding III of relay X1: +, contacts 141v1, 142x1, winding III of relay X1, —.

25 Relay X1 closes, at contact 143x1, a circuit over the vertical magnet H1 and control relay V2 by which the group selector is raised to the decade IX in which the operations for the connection of an incoming call to the connecting line ensue, +, interrupter, winding II of the relay V2, off-normal contact 144kgw, which is open when the wiper is set on the decade IX, contacts 143x1, 17c1, vertical magnet H1, contact 18w, —.

30 The relay V2 prevents premature operation of the rotary magnet D1 at contact 21v2. Relay V2 restores when the decade IX is reached and contact 144kgw is open and closes the circuit for the rotary magnet D1. The group selector hunts for an access to the calling junction line VL. When this is attained the test

35 circuit is closed: +, winding II of relay V1, contact 18c1, windings I and II of relay P, wiper 24, contact 145, conductor 52, contact 51hr, winding I of relay C4; and contact 28v1, winding II of relay C4, in parallel, contacts 29v1, 75ab, 146v8, —.

40 The relay P1 stops the group selector and disconnects the junction line at contact 31p1. The bridge consisting of the relays A1 and X1 is disconnected by the opening of the contacts 32p1, 33p1, and at the contacts 34p1 and 35p1 the speaking conductors are switched through.

45 Since in the access for the incoming connection the contacts 147c5 and 148c5 in the speaking conductors are still open, the relay G1 in the operators exchange restores. It disconnects the relays F1 and F2 at the contacts 139g1 and 140g1.

50 The selector which is set in the setting paths PGW and PLW is disconnected by the opening of contact 87f2, for relay C2 restores and opens at contact 102c2 the circuit over the relays P2 and P3 which restore and step the selectors PGW and PLW into their rest position.

55 The relay C4 energises in the locking circuit of the junction line VL closes at contact 149c4 the circuit for the slow-to-respond switching relay C5; +, contacts 149c4, 150hr, relay C5, resistance 151, —.

60 At the contacts 147c5 and 148c5 the speaking conductors are switched through. Since the relay Ra, as described above, is also energised the selected subscriber T_n is called. By a ringing current relay, not shown, the contact 152hr

65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

is opened. At certain time intervals e. g. every 5 or 10 seconds at contact 153₇ the calling current is connected to the winding II of relay Ra and also to the upper speaking conductor. When the called subscriber replies, a direct current flowing over the differential winding II of relay Ra causes the relay Ra to restore, disconnects the calling apparatus at the contacts 60_{ra} and 61_{ra} and switches through the speaking conductors at contacts 58_{ra} and 59_{ra}.

The relay C4 prevents the disconnection of the choke Dr2 from the holding bridge by closing the contact 154₄. It opens the circuit of the calling lamp AL at the contact 72_{c4}, switches in the engaged lamp BL1 at contact 155_{c4}, breaks the holding circuit of relay Ab at contact 64_{c4} so that this restores, disconnects the branch to the speaking apparatus of the operator at the contacts 68_{ab} and 69_{ab} and switches through the speaking conductors at the contacts 66_{ab} and 67_{ab}.

After the speaking conductors are switched through at the contacts 58_{ra} and 59_{ra}, relay A4 responds in the microphone feeding circuit. It switches in the relay V1 at contact 39_{a4}. Moreover it connects a holding bridge between the conductors of the junction line VL over the contacts 41_{a4} and 42_{v1} and the choke Dr1. At contact 157_{v1} the choke Dr2 is disconnected. At contact 158_{v1} a new holding circuit for the relay Hr is completed. The contact 48_{v1} is opened. At contact 159_{v1} the slow relay V8 is disconnected and by the opening of contact 146_{v8} in the energising circuit of the relay C4 makes possible the disconnection of the connecting path over the preselector I.VW and group selector IGW, at the end of the connection and by opening contact 160_{v8} ensures the restoration of relay Hr at the end of the connection.

When the subscriber Tn1 hangs up his receiver at the end of the connection the relays A4, V1 and V8 restore one after the other. By opening the contact 41_{a4} the release signal is transmitted to the distant exchange station. At contact 28_{v1} the windings I and II of relay C4 are short-circuited. Contact 40_{c4} is opened so that the relays P1 and V1 in the group selector restore and by the opening of the contacts 14_{v1} and 36_{p1} the restoration of the relay T1 in the preselector I.VW is also brought about. The group selector and the preselector are restored to their zero positions. The relay Hr is de-energised since the contact 158_{v1} is opened. The relay C4 is prevented from remaining energised over the contact 29_{v1} and the relay Hr over the contact 48_{v1} by the slow relay V8 which holds the contacts 146_{v8} and 160_{v8} open until the relays C4 and P1 or Hr have restored.

(b) *The subscriber's line engaged*

After the exchange line selector PLW has been set the test relay P3 cannot respond if the connecting line is engaged. This has the sequel that the contacts 122_{p3} and 123_{p3} remain closed. If in the metering transmitter contact 93_e is closed and thereby the circuit for relay G is completed over winding II, this relay does not remain energised owing to the high resistance of the windings I and II of relay A3, and restores. The relay A3, however, remains energised. At the contact 92_g the relay G1 is disconnected before it can attract its armatures. At contact 91_g the relay F1 is disconnected and closes its contacts 71_{f1} and 78_{f1}. Relay Br is bridged across the conductors 83 and 84 and is energised and at the

contact 162_{br} a new circuit for the slow relay F2 is closed that holds the contacts 81_{f2}, 82_{f2}, and 87_{f2} operated further. At contact 163_{br} the engaged lamp BL2 is switched in, and serves as a signal for the operator when alight that the junction line of the selected subscriber is engaged. If now the switch HT is operated and thereby switched from the branch of the junction line VL to the conductors 83 and 84 of the setting path the operator is connected with the selected subscriber's line (Tn1), for in the final selector LW the connecting-up relay Y is operated since relay P3 is not energised and by opening contacts 129_y, 132_y and closing contacts 163_y, 164_y the wiper switches through the speaking conductors.

If the calling subscriber is ready to receive the connection in question he puts down his handset and causes thereby the disconnection of the existing connection. The operator then operates the key DT. At contact 165_{dt} the relay Br is disconnected. The engaged lamp BL2 is lighted. Relay F2 is prevented from restoring by the closing of contact 167_{dt}. At contact 169_{dt} relay O is connected to the conductors 84. The relay O is an insensitive relay which in series with winding II of the relay A3 in the exchange final selector PLW is not energised.

If after the preselector I.VW has returned to its zero position the test relay P3 of the exchange final selector PLW is energised, relay Y is disconnected (at 119_{p3}) and at the contacts 124_{p3}, 129_y and 125_{p3}, 132_y, the conductors of the setting path are switched through, the relay O is energised in series with the relay R1 connected to the junction line. It holds itself energised over the contact 168_o, which is parallel to contact 166_{dt} and again connects the engaged lamp BL2 as a signal to the operator that she can return to normal the key DT. Relay F2 is held energised over the contact 170_o. After seizing the group selector I.GW the group selector is set in the manner described in Section IIa. If contact 33_{p1} is opened, the relay O is de-energised at the operator's station and disconnects the engaged lamp BL2 and the relay F2. The setting path PGW, PLW is disconnected.

II. EMBODIMENT ACCORDING TO FIG. 3

50 The junction lines VL are equipped with a single access only which is employed for outgoing as well as incoming connections.

55 Connections to outside exchanges are set up in the manner described for the calling subscriber in Section I, 1.

An incoming call from the exchange in the opposite direction and the setting of the path consisting of the selectors PGW and PLW follows as explained in Section I, 2.

(a) *Subscriber's line free*

65 The relay XI in the group selector IGW, which after the preselector I.VW is set is energised in the circuit over the conductors 84 and 134, closes, at contact 142_{x1}, a holding circuit over its winding III and over the winding III of the relay A1. The circuit of the vertical magnet H1 is closed at the contact 143_{x1}. This circuit is opened at contact 144_{kgw} when the group selector has reached the decade X in which the line is connected.

70 Relay XI by opening the contacts 180_{x1}, 181_{x1} has disconnected the bridge across the speaking conductors and by closing the conductors 182_{x1}, 183_{x1}, 184_{x1}, 185_{x1} has prepared a test circuit

over the speaking conductors connected in parallel and the relay P_1 . The contact $210x_1$ in the test circuit over the wiper 24 is opened. Thus the test relay P_1 is prevented from energising during the hunting for the calling junction line VL .

At the operator's exchange, the relay G_1 has set up, on being energised, a circuit over the relays N and M ; +, contacts $186v_3$, $187c_4$, relay M , contact $188hr$, relay N , contact $189g_1$, -. Relay N completes a holding circuit at contact $190n$. It holds the relay F_2 energised, further over the contact $192n$, opens the contacts $193n$, $194n$, and connects the conductor leading to the setting path over the contacts $195n$, $196n$ with the test apparatus consisting of the test relay P_2 and the repeater U_e . The relay M of the junction line VL prepares the locking circuit at contact $197m$, opens the contacts $198m$, $199m$ in the speaking conductors and connects the speaking conductors leading from the contact bank of the group selector over its contacts $200m$ and $201m$ with the test apparatus at the operator's exchange.

After contact $181x_1$ in the group selector is opened relay G_1 restores. Relay F_1 is disconnected. Contacts $77f_1$ and $78f_1$ are closed.

At the end of the vertical adjustment of the group selector $I.GW$, the circuit over the rotary magnet D_1 is closed at contact $21v_2$. When the wipers of the group selector reach the contacts of the calling line VL a test circuit is set up over all the connecting apparatus in use and is fed from a source (repeater U_e) at the operator's exchange, which circuit extends over the speaking conductors of the setting and speaking path connected in parallel: secondary winding s of the repeater U_e , condensers k_01/k_02 , contacts $195n/196n$, $77f_1/78f_1$, $81f_2/82f_2$, conductors $83/84$, wipers $130/131$, contacts $124p_3/125p_3$, $129y/132y$, wipers $128/133$, conductors $127/134$, contacts $9t_1/10t_1$, wipers $202/203$, contacts $32p_1/33p_1$, $182x_1/183x_1$, relay P_1 , condensers k_03/k_04 , contacts $184x_1/185x_1$, wipers $204/205$, contacts $200m/201m$, condensers k_05/k_06 , relay P_2 , secondary winding s of the repeater U_e . An alternating current source, for instance the calling source, is connected to the primary winding p_x of the repeater U_e .

The relay P_1 stops the group selector by opening its contact $206p_1$ and closes at contact $207p_1$ the test and switching circuits over the wiper 24 of the group selector.

Relay P_2 disconnects the locking circuit at contact $208p_2$. Moreover the relays P_1 and C_4 are energised: —winding II of relay V_1 , contacts $207p_1$, $18c_1$, windings I and II of relay P_1 , wiper 24 , contact 25 , winding I of relay C_4 , contacts $29v_7$, $197m$, $203p_2$, +. The relay P_1 opens the contact $22p_1$ in the circuit of the rotary magnet D_1 , short-circuits its own winding I at contact $31p_1$ and the contacts $18c_1$, $207p_1$, disconnects the test circuit by opening the contacts $32p_1$ and $33p_1$ and switches through the speaking conductors at the contacts $34p_1$ and $35p_1$. At contact $209p_1$ the holding circuit is broken over the winding III of the relays $A-1$ and X_1 . The relay C_4 holds itself energised at contact $21c_4$ in a circuit independent of the contacts $197m$ and $208p_2$ and prepares a further holding circuit at contact $40c_4$ operative after contact $28v_7$ and $29v_7$ are open. At contact $187c_4$ the circuit is opened over the relays M and N . At the contacts $198m$ and $199m$ the speaking conductors are switched through. The selected subscriber T_n

is called. At contact $192n$ relay F_2 is disconnected, the selectors PGW and PLW are disconnected.

(b) *Subscriber's line engaged*

If the test relay of the exchange final selector PLW cannot energise because the line is engaged, the switch operations described in Section I, 2b take place at the operator's exchange. The relays G and F_1 restore. Relay Er energises, holds the relay F_2 and switches in a signal for the operator. The operator connects herself to the required subscriber T_n , to which line she is connected by the closing of the contacts $163y$ and $164y$. She operates the key DT and switches in the winding I of relay O , which when the line is free and contacts $125p_3$ and $132y$ are closed is energised in series with the relay R_1 . The relays M and N are connected at contact $215o$ and relay O holds itself energised at contact $169o$. Since this holding circuit is disconnected after the marking signal for the incoming connection is received by the group selector $I.GW$ a holding circuit is set up over the winding II of the relay O at contact $213o$ independent of contact $214n$. After the group selector $I.GW$ is set on the calling line and the locking relay C_4 is energised, the relays M and N are disconnected. At contact $214n$ the holding circuit over the winding circuit of relay O is opened so that it restores. The disconnection of the setting path follows and the speaking connection is terminated.

III

The test circuit with a source of current as used in the embodiment according to Fig. 3 can naturally also be utilised in systems in which incoming connections are set up over separate accesses to the junction line. In systems in which outgoing and incoming connections are over the same accesses to the junction line, the use of a test circuit with a singular source is not absolutely necessary, if even convenient, since in this adaptation the simultaneous setting up of several incoming connections is possible without locking the outgoing direction.

The test circuit with its singular source extends in the given embodiment over the speaking conductors of the setting path connected in parallel consisting of the selectors PGW and PLW and the selectors $I.VW$ and $I.GW$ of the speaking path: subscriber's line calling connecting line. It can also extend over only one of the speaking conductors an auxiliary conductor, or for example, over the test and locking conductors of the particular selecting stage coupled by condensers.

I claim:

1. In a telephone exchange having trunk lines to another exchange, subscribers' lines, switching apparatus operable on an outgoing call from one of said subscribers' lines to extend a connection from the calling line to one of said trunk lines, and means operated on an incoming call received over one of said trunk lines to select the desired subscriber's line and then to operate said apparatus to extend a connection from the selected subscriber's line to the trunk line over which said incoming call was received.

2. In a telephone exchange having trunk lines to another exchange, subscribers' lines, switching apparatus adapted to be operated directly on an outgoing call from one of said subscribers' lines to extend a connection from the calling line to one of said trunk lines, means operated on an incoming call received over one of said trunk

lines to select the desired subscriber's line, and means controlled by said selecting of the desired subscriber's line by said last means for operating said apparatus exclusively as a hunting means to find the trunk line over which the incoming call was received and extend thereto a connection from said desired line.

3. In a telephone exchange having trunk lines to another exchange, subscribers' lines, switching apparatus having access to said trunk lines and to other lines, means for operating said apparatus directly to said trunk lines on an outgoing call to said other exchange, means including a test circuit for then causing said apparatus to search automatically for an idle one of said trunk lines and extend a connection thereto from the calling subscriber's line, means operated on an incoming call received over one of said trunk lines to select the desired subscriber's line, and means including another test circuit for then operating said apparatus exclusively as a hunting means to find the trunk line over which the incoming call was received and extend thereto a connection from said desired line.

4. A telephone exchange as claimed in claim 3, wherein one of said test circuits extends over a line conductor of the connection, and wherein the other of said test circuits is independent of the line conductors of the connection.

5. A telephone exchange as claimed in claim 3, wherein said selecting means includes means for extending a temporary connection to the desired subscriber's line, and wherein said other test circuit extends over said temporary connection.

6. In a telephone exchange having trunk lines to another exchange, subscribers' lines, switching apparatus adapted to be operated on an outgoing call from one of said subscribers' lines to extend a connection from the calling line to one of said trunk lines, other switching apparatus, means for operating said other switching apparatus on an incoming call over one of said trunk lines to extend a connection to the desired subscriber's line, means for then operating said first switching apparatus to extend a connection from said desired line to the trunk line over which said incoming call was extended to the exchange, said last means including a testing circuit extending over the connection extended by said other switching apparatus to the desired line, said circuit effective to prevent said first switching apparatus from extending a connection to any of said trunk lines except the one over which said incoming call was received.

7. In a telephone exchange having trunk lines to another exchange, subscribers' lines, switching apparatus operable on an outgoing call from any of said subscribers' lines to extend a connection from the calling line to one of said trunk lines, normally idle marking means, means effective on an incoming call over one of said trunk lines to seize said marking means, means for then operating said marking means to characterize any desired one of said subscribers' lines as a called line, means controlled by said characterizing of the desired line for thereupon automatically operating said switching apparatus to extend a connection from the characterized line to the trunk line over which the incoming call was received, means for releasing said connection at the end of the call, and means for releasing said marking means before and independently of said release of the connection.

8. In a telephone exchange having trunk lines

to another exchange, subscribers' lines, a switch common to said lines, means for seizing said switch on an outgoing call from any one of said lines and operating it to extend a connection to one of said trunk lines, means operated on an incoming call over one of said trunk lines to select the desired subscriber's line, and means controlled by said last means for seizing said switch and operating it to extend a connection to the trunk line over which said incoming call was received.

9. In an exchange as claimed in claim 8, a first test circuit in said switch effective only on outgoing calls to prevent said switch from connecting with busy trunk lines, and a second test circuit effective only on incoming calls to prevent said switch from connecting with any trunk line except the one over which said incoming call was received.

10. In a telephone system, an exchange, subscribers' lines terminating at the exchange, a two-way trunk line outgoing from the exchange, switching apparatus in the exchange having access to said trunk line over a plurality of paths, means for operating said apparatus on outgoing calls to connect the calling subscriber's line to said trunk line over one of said paths, and means for operating said apparatus on incoming calls to connect the called subscriber's line to said trunk line over a different one of said paths.

11. In a telephone system, an exchange, subscribers' lines terminating at the exchange, a two-way trunk line outgoing from the exchange, switching apparatus in the exchange common to said subscribers' lines and having access to said trunk line over a plurality of paths, means for operating said apparatus on an outgoing call from any of said subscribers' lines to connect said calling subscriber's line to said trunk line over one of said paths, and means for operating said apparatus on an incoming call to any of said subscribers' lines to connect said called subscriber's line to said trunk line over a different one of said paths.

12. In a telephone system, an exchange, subscribers' lines terminating at the exchange, a plurality of two-way trunk lines outgoing from said exchange, a switch in said exchange having access to each of said trunk lines over one path for outgoing calls and over another path for incoming calls, means for operating said switch on an outgoing call from any of said subscribers' lines to connect the calling line to an idle one of said trunk lines via its outgoing call path, means operated on an incoming call over any of said trunk lines to select the desired subscriber's line, and means controlled by said selecting of the desired line for then operating said switch to connect said desired line, via the incoming call path of that trunk line, to the trunk line over which said call was extended to said exchange.

13. In a telephone system, subscribers' lines, automatic switching apparatus common to said lines, means responsive to a calling condition on one of said lines for seizing said apparatus, means for controlling said apparatus over the calling line to extend a connection to a called line, an operator's position for controlling the extension of calls to said subscribers' lines, means controlled from said operator's position when a call is to be extended to one of said lines for simulating a calling condition on that line, thereby to cause said first means to seize said apparatus, and means controlled from said operator's posi-

tion for then operating said apparatus to extend a connection to the line by which said last line is called.

14. In a telephone system, two groups of lines, switching apparatus common to said lines, means responsive to a calling condition on any line of one group for seizing said apparatus, means for then controlling said apparatus over said calling line to extend a connection to a line of the other group, means operated when a call is to be ex- 10

tended from any line of said other group to a line of said one group for simulating a calling condition on the desired line of said one group, thereby to cause said first means to seize said apparatus, and means effective when said apparatus is seized under a simulated calling condition on the desired line to cause said apparatus to search automatically for the calling one of said other lines and extend a connection thereto.

WALTER PINELL.
